MAKING COLLAPSIBLE STRUCTURES

Vincent R. Pantalone, Hamden, Conn., assignor,
by mesne assignments, to National Folding Box
Company, Incorporated, a corporation of Con-
necticut

Application May 24, 1945, Serial No. 595,601

7 Claims. (Cl. 93—1)

1

This invention relates to the art of making collapsible structures from sheets of cardboard, paperboard or other foldable sheet material.

The invention provides a method of forming a double thickness flange on a flat blank of cardboard, paperboard or like material and has particular application to the making of tray structures for the support of merchandise between spaced upright flanges arranged on a bottom or base structure.

In the following description the invention is explained by reference to a particular application to the making of collapsible flanged trays for the support, handling, storing, packaging and shipping of stems for radio tubes. Such stems consist generally of a glass tube of considerable length with a flange shaped glass base at one end and a plurality of electrodes mounted on a glass base. The entire structure is delicate and requires very careful handling to prevent injury to the fragile and finely adjusted parts.

According to the invention a tray for the support of articles such as the aforementioned radio tube stems may be formed from a flat sheet of board by relatively few and easily performed cutting, scoring, gluing and folding operations. It is a particular feature of the invention that the trays may be pre-fabricated as flat collapsed pre-formed blanks requiring a minimum of space for storage and shipment and that the trays may be set up by a few simple folding operations to form on a base upstanding flanges between which radio tube stems may be securely supported so that the stems may be handled, shipped or stored without danger of injury.

The objects, features and advantages of this invention will appear more fully from the detailed description which follows accompanied by drawings showing for the purpose of illustration preferred embodiments of the invention.

The invention also consists of certain new and original features of construction and combination of parts hereinafter set forth and claimed.

Although the characteristic features of this invention which are believed to be novel will be particularly pointed out in the claims appended hereto, the invention itself, its objects and advantages, and the manner in which it may be carried out may be better understood by referring to the following description taken in connection with the accompanying drawings forming a part thereof in which,

Fig. 1 is a plan view of a cut and scored blank from which a tray embodying the invention may

2

be formed, the inside surface of the blank facing the observer;

Fig. 2 shows the blank of Fig. 1 after an initial gluing and folding operation;

5 Fig. 3 is a perspective view of the blank of Fig. 2;

Figs. 4, 5 and 6 are perspective views illustrating successive steps in the folding and setting up of a flanged tray from the blank shown in Fig. 3, Fig. 6 10 showing the completed tray;

Fig. 7 is a plan view of a modified form of blank;

Fig. 8 shows the blank of Fig. 7 after an initial gluing and folding operation;

15 Fig. 9 is a perspective view of the completed tray formed from the blank shown in Figs. 7 and 8;

Fig. 10 is an end view of a portion of a tray illustrating a modified manner of folding and securing an end flap of a tray of the general structure shown in the preceding drawings;

20 Fig. 11 is a perspective view illustrating the use of a plurality of trays as inserts in a carton or crate.

25 In the following description and in the claims various details will be identified by specific names for convenience. The names, however, are intended to be as generic in their application as the art will permit. Like reference characters 30 refer to like parts in the several figures of the drawings.

In the drawings accompanying, and forming part of, this description, specific disclosure of the invention is made for the purpose of explanation 35 of broader principles of the invention, but it is understood that the details may be modified in various respects without departure from the broad aspects of the invention and that the invention may be applied to other structures than the ones 40 shown.

The blank A shown in Fig. 1 may be cut and scored in multiple from sheets or rolls of cardboard, paperboard or other suitable foldable sheet material on automatic cutting and scoring machines. The blank A is subdivided by fold lines into several panels, a bottom or main panel 11 being bounded by fold lines 12 and 13 at the ends and by side edges 14 and 15 of the blank at the sides.

45 Top panels 16 and 17 are hingedly connected to the bottom or main panel 11 along the fold lines 12 and 13. Outer flange panels 18 and 19 are hingedly connected to the top panels 16 and 17 along fold lines 20 and 21. Inner flange panels 50 22, 23 are hingedly connected to the outer flange

panels 18 and 19 along fold lines 24 and 25 and securing end flaps 26 and 27 are hingedly connected to the inner flange panels 22 and 23 along fold lines 28 and 29.

The inner and outer flange panels which in the finished structure support merchandise, such as radio tube stems, are provided with suitable apertures 30, 31 and 32, 33 adapted to receive and hold the merchandise therein. Preferably the configuration of the apertures is such that the apertures 30, 31 and 32, 33 of adjoining flange panels register when the panels are folded into face to face relationship to form double thickness flanges.

The fold lines 12, 20, 24 and 28 and the fold lines 13, 21, 25 and 29 are preferably spaced equal distances from one another resulting in equal widths of the panels bounded by the fold lines.

The fold lines 20 and 21, 24 and 25, 28 and 29 may be produced in various ways to obtain any desired degree of resistance to bending of the stock at the fold lines. Thus a simple impression or scoring of the board will preserve a certain degree of resiliency of the board, while a partial cut through the stock will reduce its resistance to bending at the fold line. A similar weakening of the stock is obtained by an alternate cut and crease line. The selection of the proper kind of fold line is guided by the uses to which the tray is to be put. As hereinafter pointed out, a selective preparation of the fold lines of the blank will produce structures in which the flanges will either stand upright or have a tendency of leaning resiliently to one side or the other permitting parts to be held between flanges by clamping.

In the assembly of the blank A, adhesive *a* is first applied to the inside surface of the securing end flaps 26 and 27 and the blank is then folded about the fold lines 20 and 21 to bring the securing end flaps 26 and 27 into adhesive engagement with the inside surface of the bottom or main panel 11. The folded and glued blank A' is shown in Figs. 2 and 3 and is in condition for a final setting-up operation. The blank A' comprises two tubular structures, one on either end, formed by the inner and outer flange panels 22, 18 and 23, 19, the top panels 16, 17 and that portion of the bottom or main panel 11 which lies between the fold lines 12 and 13 and the fold lines 28 and 29 of the securing end flaps 26 and 27, respectively. The blank A' is flat and requires a minimum of space for storage and shipping. Whenever a tray is needed without further sealing or securing operations it may be set up from a blank by a few simple folding operations.

In the setting up of the blank A' the collapsed flat tubular structures at the end of the blank are first erected by moving the top panels 16, 17 and the inner flange panels 22 and 23 into a position substantially at right angles with respect to the bottom panel 11 as shown in Fig. 4. The tubular structures are then collapsed by moving the top and inner flange panels further to bring the top panels 16 and 17 into surface to surface position with the end portion of the bottom panel 11 and to bring the outer flange panels 18 and 19 and the inner flange panels 22 and 23 of each tubular structure into surface to surface position to form double thickness flanges as shown in Fig. 5.

The double thickness flanges 18, 22 and 19, 23 are then folded to stand substantially upright on the bottom panel 11. The completed tray A' is shown in Fig. 6. Its double thickness flanges 18, 22 and 19, 23 will remain in upright position

as shown in the drawing provided the hinge lines 20, 28 and 21, 29 have been weakened to substantially equal degrees. Radio tube stems 34 may then be placed in the proper apertures in the flanges which through the folding operations have been brought into registry, so that the apertures 30 and 32 register with the apertures 31 and 33, respectively.

The blank of the tray A' may be so prepared as to produce biased flanges which will either lean towards or away from each other to permit clamping of parts therebetween. The flanges will resiliently lean towards each other if the fold lines 20 and 21 are weakened less than the fold lines 28 and 29. On the other hand, the flanges will lean away from each other if the fold lines 28 and 29 are weakened less than the fold lines 20 and 21. This is easily understood when it is realized that panels connected at a hinge line will tend to return from a folded position to an aligned position due to the resiliency of the stock. The resiliency of the stock may be diminished by partial or intermittent cutting whereby the aforementioned biasing property of the tray flanges is obtained.

From an inspection of Figs. 3 to 6, particularly from Fig. 6, it is apparent that in the illustrated embodiment a certain fixed relationship exists between the height of the double thickness flanges, the spacing between the flanges, and the total length of the tray measured between the fold lines 12 and 13. In the illustrated embodiment, the flange and top panels are of equal width permitting the aforementioned erecting and collapsing of the tubular structures.

It is often desirable or necessary to have flanges of reduced height without a decrease in the over all length of the tray, the length of the tray being determined by the length of the articles to be supported thereon, in the present example, the length of the radio tube stems.

Figs. 7, 8 and 9 illustrate a modified form of blank and tray in which a reduction of the height of the flanges is obtained without a reduction of the over all length of the tray. For reasons of convenience reference numerals have been employed in identifying parts of the blank B and of the tray formed which differ from the reference numerals used in connection with the previously described embodiment by 100. Thus the bottom panel 111 corresponds to the bottom panel 11 of the blank A, the top panel 116 corresponds to the top panel 16, and so forth.

The blank B shown in Fig. 7 comprises a bottom or main panel 111 bounded at the sides by side edges 114 and 115 and bounded at the ends by fold lines 112 and 113. Fold lines 112 and 113 are interrupted by cut lines 135 and 136 leaving protruding lugs 137 and 138 on the bottom panel 111. The lugs 137 and 138 increase the over all length of the bottom panel to the distance between the cuts 135 and 136, as will more fully appear from the following description and particularly from Fig. 9 showing the completed tray.

The flat cut and scored blank B is preformed as a collapsed flat tubular structure by folding of the blank along fold lines 120 and 121 to bring the end flaps 126 and 127 into engagement with the bottom panel 111. The end flaps 126 and 127 are secured to the bottom panel 111 by gluing, stapling or otherwise.

The flat collapsed tubular blank B' is completed into tray form by a series of folding operations. The tubular structures at the ends of

the bottom panel 111 are expanded and thereafter collapsed in a similar manner as hereinbefore described and illustrated in Figs. 4 to 6.

The finished tray B'' is shown in Fig. 9. Its over all length is the distance between the outer edges 135 and 136 of the lugs 137 and 138. The tray accommodates structural parts of the length equal to the distance 135, 136, and may be used for shipping purposes as an insert in a carton or crate whose side walls or partitions are equal to or slightly greater than the distance between the edges 135 and 136 of the lugs.

It is obvious that the end flaps 26 and 27 or 126 and 127 may be secured to the bottom panel 11 or 111 in turned-under position as illustrated in Fig. 10. The drawing shows a bottom panel 11' to which the end flap 27' of a flange assembly 19' and 23' is secured in turned-under position so as to lie underneath the top panel 17' in the assembled tray.

Individual trays may be stacked and enclosed in an outer protective carton or crate 39 as indicated in Fig. 11. It is evident that in this manner a great number of fragile or delicate parts such as radio tube stems may be shipped or stored securely without danger of injury.

The invention thus provides a convenient tray or other structure which can be readily set up from a preformed flat blank without securing operations. A particular feature of the structure is its property to move and remain in set up condition by a snap action initiated by a simple folding operation. The snap action can be controlled by weakening of the fold lines and is moreover inherent in the structure due to the particular manner in which the blank is laid out and folded. Thus, the fold lines 20 and 21 for example are more weakened than the fold lines 28 and 29, even if no cut scoring or other controlled weakening is provided for. The fold lines 20 and 21 are weakened due to the fact that the stock is folded once through an angle of 180 degrees in one direction and thereafter through an angle of 270 degrees in the opposite direction. The first folding occurs when blank A is folded to form the structure A' as shown in Fig. 3. It is noted that the preparation of the structure A' as shown in Fig. 3 does not involve a weakening of the material at the fold lines 28 and 29 since the material is not yet folded at these lines. In the subsequent setting up the blank is bent 270 degrees at the fold lines 20 and 21 as shown in Fig. 5, thereby weakening the stock further at lines 20 and 21. At the same time, the bending of the stock along the fold lines 28 and 29 never exceeds 180 degrees, thereafter reduced to 90 degrees in the finished tray, as shown in Fig. 6. As a result, the resiliency of the material along the fold lines 28 and 29 is greater than the resiliency along the fold lines 20 and 21. The differential weakening thus automatically obtained by the folding operations prevents the blank from snapping back to the position of Fig. 4, whereby the structure is automatically maintained in the set up position.

Obviously the present invention is not restricted to the specific embodiments shown and described. Various modifications will be obvious to persons skilled in the art and it is clear that numerous additions, omissions, modifications and changes may be made without departure from the spirit and teaching of this invention and that the principles of the invention may be applied with equal benefit to other structures than the ones shown.

What is claimed is:

1. The method of forming a tray from a blank 75

having a bottom panel and, extending to either end of the bottom panel and hinged thereto and to one another, a top panel, an outer flange panel, an inner flange panel, and a securing flap, the method comprising, folding the blank to bring the flange panels and the securing flap on either end into overlying surface to surface position with the bottom and the top panels; securing the securing flaps to said bottom panel whereby tubular structures are formed on either end of the bottom panel; folding each tubular structure to bring the outer flange panel into surface to surface position with the respective inner flange panel and to bring the top panel into overlying surface to surface position with the bottom panel; and then erecting the flange panels into substantially upright position with respect to the bottom and top panels, whereby a collapsible tray is formed having two upstanding flanges.

2. The method of forming a collapsible tray from a flat blank having a bottom panel and, connected thereto, at either end, a top panel hinged to the bottom panel about a first fold line, an outer flange panel hinged to the top panel about a second fold line, an inner flange panel hinged to the outer flange panel about a third fold line, and a securing flap hinged to the inner flange panel about a fourth fold line, the fold lines being spaced equal distances from one another, the method comprising, folding the blank about the second fold lines and securing the end flaps to the upper surface of the bottom panel, whereby tubular structures are formed on either end of the bottom panel; erecting, and then collapsing, the tubular structures by folding the top panels about the respective first fold lines into overlying position with the bottom panel, whereby the inner and outer flange panels are brought into surface to surface position, the outer flange panels overlying the inner flange panels; and then erecting the flange panels into substantially upright position with respect to the bottom panel, whereby double thickness flanges are formed extending parallel to either end of the bottom panel.

3. The method of forming a double thickness flange on a blank having a main panel, a top panel connected to the main panel along a first fold line, an outer flange panel connected to the top panel along a second fold line, an inner flange panel connected to the outer flange panel along a third fold line and a securing end flap connected to the inner flange panel along a fourth fold line, the method comprising, folding the blank about the second fold line and securing the end flap to the upper surface of the main panel, whereby a tubular structure is formed, erecting, and then collapsing the tubular structure by folding the top panel about the first fold line, whereby the inner and outer flange panels are brought into surface to surface position, the outer flange panel overlying the inner flange panel; and then erecting the flange panels into substantially upright position with respect to the bottom panel, whereby an upstanding double thickness flange is formed on the bottom panel.

4. The method of forming a collapsible tray from a flat blank having a bottom panel, and, extending to either end of the bottom panel, and hinged thereto and to one another along fold lines, a top panel, an inner flange panel, an outer flange panel, and a securing flap, the top panel, the inner and the outer flange panel being of substantially equal width, and the inner and outer flange panel having apertures cut therein adapted to register when the inner and outer

flange panels are folded into surface to surface position, the method comprising, folding the blank to fold the outer flange panels over the adjoining top panels; securing the securing flaps to the bottom panel whereby tubular structures are formed on either end of the bottom panel; erecting and then collapsing each tubular structure to fold the top panel over the bottom panel and to bring the flange panels into surface to surface position the outer flange panel overlying the inner flange panel whereby the apertures in said flange panels are brought into registry and then erecting the flange panels into substantially upright position with respect to the bottom panel, whereby a collapsible tray is formed having two upstanding double thickness flanges.

5. The method of fabricating a collapsible tray from a flat blank which comprises cutting and scoring the blank near either end to form four parallel equally spaced score lines resulting in a division of the blank into a bottom panel bounded by side edges and two first score lines at either end, the first score lines being intermittent so as to provide spaced but aligned folding portions, the blank being cut between folding portions to provide lugs integral with the bottom panel and projecting beyond said first score lines, top panels hinged to said bottom panel along said first score lines, outer flange panels hinged to said top panels along second score lines, inner flange panels hinged to said outer flange panels along third score lines and securing flaps hinged to said inner flange panels along fourth score lines, said top panels, outer and inner flange panels being of substantially equal width, and said flange panels being cut to provide article receiving apertures adapted to be brought into registry by folding of an outer flange panel over an adjoining inner flange panel; folding the blank about the second fold lines and securing the securing end flaps to the upper surface of the bottom panel, whereby tubular structures are formed on either end of the bottom panel; erecting, and then collapsing, the tubular structures by folding the top panels about the respective first fold lines into overlying position with the bottom panel, whereby the inner and outer flange panels are brought into surface to surface position, the outer flange panels overlying the inner flange panels and the article receiving apertures lying in registry; and then erecting the flange panels into substantially upright position with respect to the bottom panel, whereby double thickness flanges are formed extending parallel to either end of the bottom panel, the lugs projecting beyond said first fold lines increasing the overall width of said bottom panel.

6. The method of forming a flange structure from a sheet of foldable board, which comprises, weakening the board in different degrees by impressing therein score lines of different magnitude to form two spaced parallel fold lines so that the

board will resist bending at one fold lines less than at the other, and scoring the board along an intermediate fold line lying between said spaced fold lines, said three lines defining two flange panels of equal width hinged along said intermediate fold line; and then folding said two flange panels into face to face position along said intermediate fold line whereby said other two fold lines are brought into alignment, and folding said flange panels along said other two fold lines with respect to the remainder of the board while leaving the flange panels in face-to-face position, whereby a double thickness flange is formed biased to lean towards one side or the other depending on the differential weakening of said other two fold lines.

7. The method of forming a flange structure from a sheet of foldable board scored to provide four parallel equally spaced fold lines there-across, two intermediate fold lines lying between two outer fold lines, the said four fold lines defining three panels of equal width, including two flange panels hingedly connected along one of said intermediate fold lines and a third panel hinged to one of said flange panels along the other intermediate fold line; a main panel extending to one side of the said three panels along one of the outer fold lines; and a securing panel extending to the other side of the three panels along the other outer fold line, the sheet being folded back upon itself about the other of said intermediate fold lines, the securing panel being secured face-to-face to said main panel, whereby a flat collapsed tubular structure is formed of the sheet, the method comprising, squaring the tubular structure by folding said third panel into an upright position with respect to said main panel, whereby a hollow structure is formed; then recollapsing the tubular structure by continuing the folding of the said third panel into a position substantially 180 degrees with respect to its initial position, whereby the hollow structure is flattened and the flange panels are brought face-to-face; and then erecting the flange panels into up-standing position with respect to the main and third panel.
